UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

MIXTURE-FORMING MEANS FOR INTERNAL-COMBUSTION ENGINES.

Applicaton filed December 9, 1920. Serial No. 429,587.

This invention relates to mixture forming means for internal combustion engines, and particularly to means for controlling the proportion of air and liquid fuel.

5 In internal combustion engines as used on airplanes, the carburetor is usually provided with some sort of mixture proportion control or means for lessening the feed of the liquid fuel so that the most nearly correct proportion of air and liquid fuel may be maintained when the air pressure drops as it does at the higher altitudes reached by the airplane.

With the use of combustion heaters, particularly of the suction type, such as shown 15 in Patent No. 1,448,651, dated March 13, 1923, on airplane engines, it was found that the mixture for the combustion heaters, if fed by separate carburetors must also be weakened but not necessarily to the same extent as the 20 mixture for the main carburetor. It is one of the objects of the present invention therefore to provide mixture proportion control means for such auxiliary carburetors as well as for the main carburetor, preferably with 25 interconnecting means for simultaneously operating the controls. By this arrangement the degree of change in the mixture can be different in the main and auxiliary carburetors respectively and yet the mechanism 30 may be operated in unison by a single lever.

It has also been found that a mixture control involving means for imposing a partial vacuum on the float chamber is rather delicate in adjustment or operation and one of 35 the objects of the present invention is to definitely limit the amount of depression which may be imposed on the float chamber in such a mixture control mechanism.

In the use of a suction operated combustion 40 heater such as above referred to, the suction on the heater is greatest and consequently the suction on the auxiliary carburetor is greatest when the throttle valve of the engine is in nearly closed or idling position and at this 45 time the suction is practically nothing below the throttle valve. For this reason the mixture proportion control can not be obtained for the auxiliary carburetor if variations in the float chamber depression of the main carburetor is depended upon for the purpose. It is one of the objects of the present invention to obviate this trouble by providing independently operating mixture proportion

control means but which may be brought into operation simultaneously with the mixture proportion control means of the main carburetor.

Other objects of the invention will appear from the following description taken in connection with the drawings, which form a part 60 of this specification, and in which:

Fig. 1 is a vertical section through the intake pipe of an internal combustion engine and mixture forming and feeding means embodying this invention;

Fig. 2 is a horizontal section on the line 2—2 of Fig. 1;

Fig. 3 is a section on both of the lines 3—3 of Fig. 1, through the caps and upper ends of the valves of the float chambers;

Fig. 4 is a section similar to Fig. 1, illustrating another form of the invention;

Fig. 5 is a horizontal section on the line 5—5 of Fig. 4.

Referring particularly to Figs. 1, 2 and 3 75 of the drawings, 10 represents the intake pipe of an internal combustion engine and 11 is a carburetor connected to the intake pipe with the upper part forming a continuation of the intake pipe. A throttle valve 12 is 80 arranged at a suitable point in the intake passage above the mixing chamber of the carburetor.

The carburetor 11 has a float chamber 13 with a float 14 and valve 15 of the usual type 85 and operating in the well known manner to maintain the level of liquid in the float chamber at the desired height. The liquid fuel is fed from the float chamber 13 through a conduit 16 to a nozzle 17 which is arranged 90 in a Venturi tube 18. The main air intake 19 of the carburetor feeds the Venturi tube and an auxiliary air intake 20 feeds additional air above the Venturi tube, thus producing the desired mixture for operating the engine. 95

As the invention is illustrated in Fig. 1, the mixture forming means is adapted for use in an airplane or dirigible engine or other machine that is intended to operate at altitudes considerably above sea level. It is 100 also intended for use with a combustion heating device which is operated by the suction of the engine above the throttle valve and if more than one of such heaters is used the two auxiliary carburetors hereinafter described may be employed with them. If a

single combustion heater is used, only one of such auxiliary carburetors would be ordinarily required. Only one of them will consequently be described and it is understood 5 that the other is identical with it.

The auxiliary carburetors referred to are indicated at 21 and they are mounted in a float chamber 22 which is shown as cast integral with the main carburetor 11, but it 10 may be separately formed if desired. The usual float 23 and valve 24 are shown for maintaining the liquid level and an air vent 25 is shown in the cap 26 for maintaining atmospheric pressure in the float chamber. 15 The upper end of the valve 24 is flattened as at 27 to permit the air to enter the float chamber. This is more clearly shown in Fig. 3.

The main body piece 28 of the carburetor 21 is threaded into a boss 29 formed in the 20 cover of the float chamber, and its lower end extends into the gasoline or other liquid fuel in the float chamber. This lower end forms a well 30 fed by a restricted opening 31 and cross channels 32, as well as by air openings 25 33 at the upper part of the well. A central mixture channel 34 extends upwardly through the body and terminates in cross channels 35 near the upper pointed end of the body. A sleeve 36 surrounds the upper 30 part of the body and is somewhat contracted adjacent the cross channels 35 and terminates at its upper end in a connection 37 for a pipe 38 which conveys the mixture formed by the carburetor to the combustion heater device 35 above referred to (not shown). Air ports 39 and vertical channels 40 supply air to the sleeve 36, which air is added to the emulsion brought up by suction through the channel 34 to form the desired mixture for the normal 40 operation of the combustion heater device at sea level.

It will be understood that the main carburetor 11 and the auxiliary carburetor 21, as hereinabove described, are not new in themselves and are not claimed per se herein. Other forms of carburetors for accomplishing the same purpose may be substituted and used with the combinations of elements 45 hereinafter described and claimed.

For the purpose of obtaining mixture proportion control of the main carburetor 11 under various atmospheric conditions, that is, for instance, for restricting the liquid fuel feed as the air becomes less dense, a valved 50 connection is provided between the float chamber and the intake pipe. This connection is in the form of a pipe 41 which extends from the cap 42 on the cover of the float chamber 13, to the intake pipe 10 below the 55 throttle 12 so that the suction on the float chamber will correspond to the suction on the air intake passages of the carburetor. The opening 43 into the intake pipe is somewhat restricted so that the air that may be drawn 60 into the carburetor will not materially affect 65

the mixture. A valve 44 is provided in the pipe 41 to control the connection, the operation of this valve to be either automatic by a suitable altitude device or manual by the operator. As shown in Fig. 1, the valve 44 is 70 closed, which is its ground or sea level position and in use it will be gradually opened as the machine ascends to the higher altitudes. When it is opened the suction of the carburetor will be communicated to the upper part 75 of the float chamber, thus creating a partial vacuum therein and thereby partly neutralizing the suction at the nozzle 17. A small vent 45 is made in the cap 42 to somewhat modify the suction, but even with this vent 80 it has been found difficult to properly control the suction and in some cases the depression in the float chamber becomes so great that too little gasoline or liquid fuel is fed to the carburetor. To offset this possibility and definitely limit the amount of depression which 85 may be imposed on the float chamber 13, a submerged vent is provided for the float chamber. This is shown in the form of a parallel chamber 46 drilled vertically in the casting forming the float chamber, connected near its lower end with the float chamber by a port 47 and open to the atmosphere at its upper end as through the ports 48. This is 90 on the principle of a U-tube and it will be seen that the depression in the upper part of the float chamber will tend to lower the level of the liquid in the chamber 46 until the point is reached when the port 47 is uncovered and thereafter air will be drawn into the float 95 chamber thereby preventing further depression therein. In this manner the maximum depression in the float chamber may be fixed without the use of minute and accurately sized orifices communicating with the atmosphere, such as are sometimes employed for 100 this purpose.

The auxiliary carburetors 21, it is understood, operate at their maximum when the main carburetor 11 is operating at its minimum, because of the greater pull on the suction operated combustion device at that time. These carburetors 21 therefore are provided with a separate mixture proportion control means, in the form of an additional air inlet 110 49 for each of them. These air inlets are fed by pipes 50 and a pipe 51, the intake end of the latter being controlled by a valve 52. As shown, the valve 52 is closed which is the ground or sea level position of this altitude 115 control device. As the valve 52 is gradually opened air in the desired quantities is fed to the additional air intake 49 then consequently to the carburetor 21, thus making a leaner 120 mixture.

The valve 44 of the main carburetor and the valve 52 of the auxiliary carburetors, are interconnected by a rod 53, and a rod 54 is provided for automatic or manual adjustment of these valves so that the control means of 125 130

both carburetors may be simultaneously operated as the machine reaches the higher altitudes.

Referring to the form of the invention shown in Figs. 4 and 5, the following parts are the same as in Fig. 1: intake pipe 10, main carburetor 11, throttle valve 12, float chamber 13, float 14, valve 15, passage 16, fuel nozzle 17, Venturi tube 18, main air intake 19 and auxiliary air intake 20. The auxiliary carburetors 21 are also exactly the same in construction and function. So far as maintaining the liquid level for the auxiliary carburetors 21 is concerned, the float chamber 23, the float 23 and the valve 24 are also the same as in Fig. 1, and the connections and piping 37 and 38 respectively, from the carburetors 21 are the same.

The mixture proportion control for the main carburetor 11 is also substantially the same as that of Fig. 1, since there is a pipe 41 leading from the cap 42 of the float chamber 13 to the intake pipe 10 through a restricted opening 43. A vent 45 is also provided in the cap 42. However, instead of breaking the connection formed by the pipe 41 for ground operation of the device, a valve is used for admitting atmospheric pressure to the pipe, as will be hereinafter described.

The float chamber 13 of the main carburetor is provided with the same submerged vent as in Fig. 1, comprising the chamber 46, port 47 and air port 48.

For the float chamber 22 there is also an air vent 25 in the cap 26 similar to Fig. 1, but instead of the control for the carburetors 21 shown in Fig. 1, this form of the invention provides a suction connection from the cap 26 to the intake pipe 10 above the throttle. This connection is in the form of a pipe 60 connected at one end to the cap 26 and at the other end to the intake pipe 10 through a restricted opening 61. Thus the suction or depression in the intake pipe 10 above the throttle, is communicated to the upper part of the float chamber 22 in the same manner that the depression in the intake pipe 10 below the throttle valve 12 is communicated to the upper part of the float chamber 13.

With this construction, the float chamber 22 is also provided with a submerged vent for the purpose of definitely limiting the amount of depression which may be imposed on the float chamber. This submerged vent is shown in the form of a chamber 62, a port 63 communicating with the float chamber 22 below the level of the liquid therein, and an atmosphere port 64 at its upper end. It will be seen that the submerged port 63 is somewhat lower than the corresponding port 47 of the float chamber 13 as it is frequently desirable to have a higher limit for the depression in the auxiliary carburetor float chamber than in the main carburetor float chamber.

It will be obvious that if the pipes 41 and

60 are opened to the atmosphere their effect on the float chambers 13 and 22 will be nullified and in that event said float chambers are fed normally as is desired for ground or sea level operation. For accomplishing this a valve 65 is provided, this valve having an air port 66 and channels 67 and 68 which communicate respectively with the pipes 41 and 60. The valve is operated by a rod 69 either automatically or manually by the operator and as it is turned it gradually vents the pipes 41 and 60 until it is fully opened when the operation of the suction in those pipes is entirely nullified.

An engine such, for instance, as that shown in Patent No. 1,448,651, when equipped with this invention, will have certain advantages that are of considerable importance. Thus, suppose an engine so equipped is used in an airplane operating at a ten thousand foot altitude and it is desired to glide down with the engine running idle. Under these conditions it is preferable to idle the engine during the glide rather than shut it off entirely because under the latter condition there would be the uncertainty of starting the engine when nearing the ground and that is when it is most needed. On this glide downwardly the throttle would be nearly closed and there would be considerable suction above the throttle and practically none below it. The combustion heater is subject to the suction above the throttle valve and under these conditions, therefore, it would be operating at its maximum and this would keep the intake passages and the gas being fed to the engine at their maximum heat and the engine would not stall as its throttle is opened when nearing the ground. At the same time the engine would be getting a richer mixture from the main carburetor because of the altitude and because of the fact that there would be little suction below the throttle and consequently slight depression in the float chamber. That is the kind of mixture the engine needs for idling. But the combustion heater does not require a rich mixture under these conditions because it is operating at its maximum. If the auxiliary carburetor, that is the carburetor used for the combustion heater, operated similarly to the main carburetor, the same rich mixture would go to the combustion heater and probably it would be too rich to burn and stalling of the engine just at the time the aviator needed it most, that is when nearing the ground, would probably result. With applicant's invention the auxiliary carburetor is automatically controlled to give the proper mixture under these conditions and the fatal result above referred to is avoided. With applicant's invention the maximum operation of the combustion heater is assured and a desirable rich mixture for the engine results, when those two conditions are most needed in the operation of an airplane.

It will be understood that various forms other than those described herein may be used without departing from the spirit or scope of the invention.

5. Having thus described my invention, what I claim and desire to secure by Letters Patent is:

10. 1. In an internal combustion engine the combination with two float chambers and two carburetors connected thereto respectively, mixture proportion control means connected to both of said float chambers, and a single valve for operating said control means to vary the mixture proportions.

15. 2. In an internal combustion engine, the combination with an engine intake pipe having a throttle valve therein, a carburetor connected to said pipe to supply mixture thereto and having a float chamber, a second float chamber, a carburetor fed by said second float chamber, a pipe connection between one of said float chambers and the intake pipe below the throttle valve, and a pipe connection between the other said float chamber and the intake pipe above said throttle valve.

20. 3. In an internal combustion engine, the combination with an engine intake pipe having a throttle valve therein, and a carburetor connected to said intake pipe and having a float chamber, a carburetor adapted to supply a combustion heater having a float chamber, a pipe connection from the main carburetor float chamber to the intake pipe below the throttle valve, and a pipe connection from the second named carburetor float chamber to the intake pipe above the throttle valve.

25. 4. In an internal combustion engine, the combination with an engine intake pipe having a throttle valve therein, and a carburetor connected to said intake pipe and having a float chamber, a carburetor adapted to supply a combustion heater having a float chamber, a pipe connection from the main carburetor float chamber to the intake pipe below the throttle valve, a pipe connection from the second named carburetor float chamber to the intake pipe above the throttle valve, and valve controlled means for breaking the suction in both of said pipe connections.

30. 5. In an internal combustion engine, the combination with the intake pipe thereof having a throttle valve, of a carburetor connected to said intake pipe and having a vented float chamber, a pipe connecting the upper part

of said float chamber to the intake pipe below the throttle valve, a valve in said pipe, and a submerged vent means for the float chamber.

35. 6. In an internal combustion engine, the combination with the intake pipe thereof having a throttle valve, of a carburetor connected to said intake pipe and having a vented float chamber, a pipe connecting the upper part of said float chamber to the intake pipe below the throttle valve, a valve in said pipe, and a chamber arranged parallel to the float chamber and open to the float chamber below the liquid level therein, said parallel chamber being open to the atmosphere at its upper end.

40. 7. In an internal combustion engine, the combination with the engine intake pipe, of mixture forming means comprising two float chambers, means connecting the upper part of one of said float chambers with said intake pipe below the throttle valve thereof, means connecting the upper part of the other said float chamber with the intake pipe above the throttle valve thereof, and submerged vent means for each of said float chambers.

45. 8. In an internal combustion engine, the combination with the engine intake pipe, of mixture forming means comprising two float chambers, means connecting the upper part of one of said float chambers with said intake pipe below the throttle valve thereof, means connecting the upper part of the other said float chamber with the intake pipe above the throttle valve thereof, and submerged vent means for each of said float chambers, the submerged vent of one of said submerged vent means being lower than that of the other.

50. 9. In an internal combustion engine, the combination with the engine intake pipe, of mixture forming means comprising two float chambers, means connecting the upper part of one of said float chambers with said intake pipe below the throttle valve thereof, means connecting the upper part of the other said float chamber with the intake pipe above the throttle valve thereof, and submerged vent means for each of said float chambers, the submerged vent means of the last mentioned float chamber being lower than the other submerged vent means.

In testimony whereof I affix my signature.

LIONEL M. WOOLSON.
